SUSPENSION DISTRIBUTING SYSTEM

Heinrich Fläig and Adolf Stark, Heidenheim, Germany, assignors to J. M. Voith G.m.b.H., Maschinenfabrik, Heidenheim (Brenz), Germany

Filed May 4, 1959, Ser. No. 810,618

Claims priority, application Germany May 9, 1958
12 Claims. (Cl. 162—342)

This invention relates to a distributing system for suspensions and more particularly to suspension inlets for dehydrating machines and stock inlets for paper-making machines.

It thus relates to distributing systems for such machines which are to effect a perfectly even distribution of a fibrous suspension supplied through a feed pipe over the entire width of a band or, for instance, a Fourdrinier wire in a paper-making machine, the width of which band is much larger than the diameter of the aforesaid feed pipe. Furthermore, the distribution must be effected in such a manner that the formation of deposits of the suspended matter and the occlusion of air in the feeding and distributing devices is practically eliminated.

The known devices generally comprise a feeding line or pipe means, a distributor for the stock or other suspension, and a headbox from which the suspension is discharged as a wide band.

In paper-making and similar machines, the fibrous suspension or stock is generally conveyed from a machine chest via a stock regulator, refining devices and purifying devices such as screeners, hydrocyclones or the like, and finally through the above-mentioned feed pipe to the wire of the paper making machine. This involves the problem of converting the flow of stock through the feed pipe of, in most cases, circular cross-sectional area, to a stream of rectangular cross-sectional area corresponding in width to that of the machine wire. Moreover, this conversion must be effected in such a manner that the quantity and velocity of the stock leaving the rectangular, mostly slot-shaped discharge gate of the headbox must be completely uniform over the entire width of the machine wire, as the fiber web to be produced on the wire is to be of even thickness and weight over that entire wire width.

A known device for achieving a uniform flow in the headbox of a stock inlet for paper making machines is described in Patent 2,677,991 (German Patent 808,081), and comprises a wide closed pond chamber, a deceleration section extending upwardly toward the chamber, and a wide downwardly extending acceleration section. The stock is delivered first to a distributor box and from there to a slot-shaped entrance of the aforesaid deceleration section of the headbox. In the latter section which is devised as a diffusor with upwardly diverging walls, the stock velocity of flow is decreased and a distribution and direction of the flowing stock is attained by providing several perforated rolls across that section. The deceleration diffusor-type section opens with its larger, upper end into the aforesaid pond chamber the upper part of which encloses an air cushion. From this pond the stock flows downwardly into a long, narrow accelerating section from which it emerges by way of a slot-shaped gate on to the machine wire. This known device requires very large dimensions in order to attain the desired effects of sufficient deceleration and acceleration, and constructions 30 feet high have been built in practice.

Therefore, another known device has the object of attaining a uniform flow of stock already in the stock distributor preceding the headbox and thereby obtaining a much more compact stock inlet device of greatly reduced dimensions compared with that of Patent 2,677,991 more recent device, which is described in German Patent

2

851,301, assigned to the same assignee as the present application. This device comprises a stock distributor having one or several primary distributing chambers which are connected by way of one or several conduit means to a secondary common distributing chamber arranged, in the direction of stock flow, subsequent to the aforesaid primary distributing chamber or chambers. Communication between the primary distributing chamber or chambers and the secondary chamber is effected through a slot-shaped gate arranged at the central region of the primary distributing chamber or chambers. However, this has the drawback that the suspension enters the secondary chamber in the form of a jet which is only relatively incompletely disintegrated in space owing to the short distance available for such spatial disintegration in the secondary distributing chamber. Therefore, the distribution of stock flow in this secondary chamber does not take place with a completely satisfactory degree of uniformity, wherefore a further additional device for uniform distribution of the stock in the headbox is indispensable. Moreover, the connection of the aforesaid conduit means to the central region of the primary chamber suffers from the drawback that air cushions may form in the upper portion of this chamber and lead to the formation of fiber lumps or deposits.

It is, therefore, the object of our invention to provide a distributing device of the type comprising several successively arranged distributing chambers for connection to and preceding a headbox or the like discharge means for suspensions such as, in particular, fibrous suspensions or stock, in the direction of flow of the suspension, which distributing device avoids the above-described drawbacks and permits to attain a satisfactorily uniform distribution of the suspension over the entire width of the band onto which it is to be discharged and to establish the conditions of flow required at such discharge, already in the distributing device prior to the entrance of the suspension into the headbox or a corresponding discharging device.

40 The term "dehydrating machine" where used in this specification and the appended claims includes paper-making machines and the like.

The term "suspension" as used in this specification includes all non-colloidal two phase systems comprising a solid and a liquid phase, and more particular suspensions in which the liquid phase is water and the solid phase is a fibrous material.

This object is attained by the suspension distributing device according to our invention which comprises, interposed in the path of flow of the suspension through a supply line of substantially circular or similar cross section to a headbox for the discharge of the suspension in a transversely widened band, two successively arranged distributing means, of which the first means is in communication with the aforesaid supply line and comprises at least one, or several, primary distributing chambers, communicating all to a common, subsequently arranged secondary distributing chamber, and characterized in that the communication between the primary distributing chamber or chambers and the secondary common distributing chamber is effected by way of an opening disposed in the uppermost zone of the primary chamber or chambers and a diffusor-type section, two opposite ones of the walls of which diverge from said opening in the primary distributing chamber to merge at its widest cross section into the secondary chamber.

This combined feature of a diffusor-shaped entrance into the secondary distributing chamber with the arrangement of the opening leading to the diffusor at the uppermost zone of the primary distributing chamber or chambers, where several of the latter chambers are connected in

parallel to the secondary chamber, offers the advantages of creating favorable conditions of flow in the suspension passing therethrough and of causing a continuous removal of the air entrained in the suspension, thereby avoiding the formation of air cushions leading to undesirable deposits of solid matter in the apparatus.

If the suspension to be distributed is fibrous suspension such as paper stock, the diffusor section merging with the secondary distributing chamber can be relatively short and have the two opposite diverging walls open by an angle of at least 8° and preferably about 30° , and is provided with one or several auxiliary distributing members arranged in the path of stock flow.

The secondary distributing chamber has a length, in a direction transverse to that of the movement of the suspension therethrough, which length is about equal to the width of the suspension band to be formed, for instance, on a Fourdrinier wire.

These features in the diffusor section in the distributing device according to the invention achieve that the suspension jet emerging from the primary distributing chamber gradually spreads in the diffusor section and that the suspension is so strongly decelerated that its velocity is almost equal to zero in the second distributing chamber, which latter velocity would have to be attained in order to achieve an ideal equalization of pressures and velocities in the suspension.

This equalization of the flow velocities in the interior of the diffusor is essentially facilitated by the above-mentioned arrangement of auxiliary members; furthermore these members prevent the creation of non-laminar flow which would involve a separation of the boundary layer of fluid from the diffusor walls.

Tests carried out in practice have confirmed that the various features of the distributing device according to the invention make it possible to attain an almost ideally uniform distribution of pressure and velocity over the entire width of the slot-shaped outlet opening of the secondary distributing chamber, by way of which opening the distributing device is, for instance, connected to the headbox of a paper-making machine.

It is, therefore, not necessary to arrange further auxiliary distributing members in the headbox, so that the dimensions of the latter can be held considerably smaller than in the known stock inlet systems. Of course, one or several rotary defloccing members may nevertheless be provided to prevent flocculation of the stock in the headbox.

The auxiliary distributing members arranged in the diffusor section of the secondary distributing chamber may be perforated rolls as described in Patent 2,677,991; baffle rolls or rectifier rolls of the type described in Patent 2,699,096; cage type rolls as described in Patent 2,737,087 and, in fact, any other suitable known type of rolls. These rolls can be arranged in different manners in the interior of the diffusor as will be explained further below.

Generally, the use of a single perforated roll in the diffusor section connected to the primary distributing chamber leads to a radially spreading expansion of the flow of the stock. In order to avoid the uneven distribution of flow velocities causing this phenomenon, a plurality of rolls either in series, or in a parallel arrangement, is provided with the axes of the rolls located on an arc, the center of which is located in the direction toward the entrance from which the stock flows into the diffusor section.

Certain suspensions such as in particular suspensions of textile fibers do not permit the use of auxiliary distributing members in the diffusor. In this case, the diverging walls of the distributor section of the secondary chamber in the distributing system according to our invention should diverge by an angle from about 3° to maximally 8° . Hence, the diffusor section is built correspondingly longer. No auxiliary distributing members

will then be provided in the interior of the diffusor section.

The longer construction of the diffusor section for distributing this type of fibrous suspensions is warranted by the almost ideal equalization of pressure and velocities over the entire width of the suspension band leaving the secondary distributing chamber. The velocity equalization achieved in this arrangement is much better than if the conduit between the primary and secondary distributing chambers were only a slot-shaped opening.

In order to obtain a favorable transitional flow from the primary chamber, or chambers to the diffusor section of the secondary chamber, it is preferred to provide a short-shaped conduit of substantially constant, preferably rectangular cross sectional area between outlet opening of the primary chamber and the entrance to the diffusor section.

The invention will be further explained in detail hereinafter in connection with the accompanying drawings in which

FIGURE 1 shows in perspective and partly sectional view a suspension distributing system equipped with an embodiment of the distributing device according to the invention, and which is particularly adapted as a stock inlet for paper-making machines;

FIGURE 2 is a schematical view of a different embodiment of the distributing device according to the invention;

FIGURE 3 shows schematically a further embodiment of the distributing device according to the invention, comprising two primary distributing chambers and a common secondary distributing chamber;

FIGURE 4 shows schematically yet another embodiment of the distributing device similar to that shown in FIGURE 3; and

FIGURE 5 is a sectional view of another suspension distributing device according to the invention, which device is particularly suited for discharging a wide band of a suspension of textile fibers, which do not permit the use of auxiliary distributing means such as perforated rolls and the like.

Referring now to the drawings more in detail, the suspension distributing system illustrated in FIGURE 1 and suitable as a stock inlet for a paper-making machine equipped with a Fourdrinier wire 1 which system comprises interposed between a stock feed pipe 2 of, for instance, circular cross section, and a headbox 4 according to the invention an embodiment of the suspension distributing device.

This entire distributing device is designated by reference numeral 3, and comprises a single primary distributing chamber 5 the cross sectional area of which approximates a circular area, so that the entire chamber 5 is of approximately tubular configuration, a slot-like opening 5a in the cylinder wall merging into a short passageway 6 of substantially constant rectangular cross sectional area, which opening 5a opens in the uppermost zone 5b of chamber 5, a flow decelerating diffusor section 7 connected with its narrower opening to the passageway 6 so as to be in communication, through the latter, with the aforesaid primary chamber 5. The decelerating diffusor section 7 has divergent opposite walls 26 and 27, being the top and bottom walls, respectively, while the side-walls of the diffusor section 7 one of which is shown at 22 may be either parallel with each other or divergent from the narrowest, rectangular cross sectional area at the opening of passageway 6.

In the embodiments shown in FIGURES 1 and 2, the diffusor section 7 is devised with a divergent angle of approximately 30° . In the interior of this section and behind the entrance thereto from passageway 6, there is provided a perforated roll 19 as an auxiliary rotary distributing member, so as to further improve the evenness out of the flow conditions of the suspension. Roll 19 has a ratio of perforations to entire cylindrical surface of about 25 to 30%.

The high opening angle of about 30° of the diffusor section 7 in combination with the provision of roll 10 permits to build the diffusor section 7 relatively short.

The diffusor section 7 merges into a secondary distributing chamber 8, walls 26 and 27 of the former being continued by the approximately semicircular end wall 28 of the latter chamber 8.

This secondary distributing chamber 8 is provided with a slot-shaped outlet 9 extending over substantially the entire width of the secondary chamber 8 in the uppermost zone 8a of that chamber. To the outlet 9 of chamber 8 there is connected the stock entrance of headbox 4 which is devised preferably as a short decelerating section 12, with divergent side walls 12a and 12b, the latter of which is slightly inclined out of the vertical plane, so that this section has an axis slightly inclined from the vertical.

Headbox 4 is further provided with a conventional slot-shaped stock discharge nozzle 13 from which the stock is transferred on to wire 1; inside the headbox 4 and in front of nozzle 13 there is provided another rotary member in the form of a perforated roll 14.

This roll 14 has a much larger ratio of open surface to total surface than roll 10, namely, about 55%. This roll serves primarily to prevent flocculation of the suspension and less to perfect distribution conditions, since the stock or other suspension arrives already perfectly well evened from outlet 9.

In FIGURES 2, 3, and 4, the headbox 4 has been omitted to simplify the drawings. Feed pipe 2 has been shown schematically as connected by flange means to the primary chamber 5 or to the primary chambers 16, 17 or 16a, 17a in FIGURES 3 and 4. It will be noted that, while pipe 2 opens into the cylindrical wall of chamber 5, similar to the arrangement shown in FIGURE 1, the feed pipes 2 in FIGURES 3 and 4 are connected to the end walls 22 of chambers 5 as indicated in phantom lines at 2' in FIGURE 1.

The embodiment shown in FIGURE 2 differs from that of FIGURE 1 in that the diffusor section 7a extends upwardly instead of horizontally away from passageway 6, as is the case in FIGURE 1. Passageway 6 in this embodiment is very short.

Apart from perforated roll 10, a second rotary distributing member, for instance, a rectifying roll 15 of larger diameter than roll 10, is arranged in series subsequent to roll 10 in the interior of diffusor section 7a.

In the embodiment shown in FIGURE 3, the distributing system according to the invention comprises two primary distributing chambers 16 and 17 and connected thereto, in a manner similar to that described in connection with FIGURE 1, diffusor section 7b associated with chamber 16, and diffusor section 7c associated with chamber 17. The chambers 16 and 17 are of square cross section in this embodiment. Both diffusor sections 7b and 7c merge into the common secondary distributor chamber 18 at the uppermost zone of which there is provided outlet 19, to which a headbox or the like can be connected.

A plurality of auxiliary distributing members in the form of perforated rolls 10a is mounted in the interior of diffusors 7b and 7c. Each of the groups of members comprises five, two aligned in a first row across the distributor section and immediately in front of passageway 6, and three more aligned with each other in a second row behind and in staggered relation to the first row of rolls.

In the embodiment of the invention shown in FIGURE 4, the distributing system also comprises two primary distributing chambers 16a and 17a adjacent each other, each with a longer passageway 6b, 6c opening into a diffusor section 7d, 7e, respectively. The two diffusor sections 7d and 7e which merge into the common secondary chamber 18a, are arranged with their axes of flow parallel to each other, while these axes form an angle

5 β of about 90° with each other in the embodiment shown in FIGURE 3.

In the interior of diffusors 7d and 7e, groups of three perforated distributing rolls 10b are arranged with their axes on arcs the centers of which are located on the side of the passageways 6b, 6c. A headbox may be connected in the same manner as illustrated in FIGURE 1, to the outlet 19 of secondary distributing chamber 18a.

Finally, if suspensions of textile and the like fibers are to be distributed, the fibrous material which does not permit of the use of auxiliary distributing rolls, an embodiment of the distributing system according to the invention of the kind illustrated in FIGURE 5, can be used. This distributing system is similar to that illustrated in FIGURE 1, with the difference that the diffusor section 37 connected to a short passageway 36 from primary chamber 5, is greatly elongated and that the walls 38 and 39 diverge by a much smaller angle α' than the walls 26 and 27 in the embodiment of FIGURE 1. The divergence angle α' in the embodiment of FIGURE 5 ranges from about 3° to 8° only. The ratio of diffusor length L to the diameter D of the secondary distributing chamber is about 9:1 in the embodiment shown in FIGURE 5, while it is about 2:1 in the embodiment shown in FIGURE 1, and about 3:2 in the embodiment shown in FIGURE 2. In the embodiment shown in FIGURE 5 that ratio may conveniently vary from about 5:1 to 10:1 and higher depending on the exact nature of the suspension.

It will be understood that these ratios are given by way of example only, while the ratio L:D can be varied within considerably wider limits. Also the number of distributing chambers can be greater than two, for instance, three, four, or five etc. Furthermore, the passageway between the primary distributing chamber and the diffusor section may be subdivided to form several communicating paths between the two spaces, or several passageways from one and the same primary chamber may communicate each with one diffusor section, all diffusor sections then merging into one and the same secondary distributing chamber.

It will be understood that this invention is susceptible to modification in order to adapt it to different usages and conditions and, accordingly, it is desired to comprehend such modifications within this invention as may fall within the scope of the appended claims.

We claim:

1. A distributing system for suspensions of fibrous materials to be supplied through feed pipe means to the system and delivered from there to a dehydrating machine, comprising, in combination, a headbox, one primary distributing chamber to which said feed pipe means are connected, said primary distributing chamber having one outlet slit-shaped opening in the uppermost part thereof; a secondary distributing chamber having one diffusor section merged therewith, said diffusor section having an entrance opening and two opposite walls extending over the whole length of the primary and secondary distributing chambers and diverging from said entrance opening towards said secondary distributing chamber, said diffusor section being connected by way of said entrance opening to said outlet opening in said primary distributing chamber, said secondary distributing chamber having an outlet in the highest part for connection of said headbox thereto.

2. A distributing system for suspensions of fibrous materials to be supplied through feed pipe means to the system and delivered from there to a dehydrating machine, comprising, in combination, a headbox, one primary distributing chamber to which said feed pipe means are connected, said primary distributing chamber having one outlet slit-shaped opening in the uppermost part thereof; a secondary distributing chamber having one diffusor section merged therewith, said diffusor section having an entrance opening and two opposite walls extending over the whole length of the primary and secondary distribut-

ing chambers and diverging from said entrance opening towards said secondary distributing chamber by an angle of at least 8° up to approximately 30°, said diffusor section being connected by way of said entrance opening to said outlet opening in said primary distributing chamber, and further comprising at least one rotary auxiliary distributing member in said diffusor section, said secondary distributing chamber having an outlet in the highest part for connection of said headbox thereto.

3. A distributing system as described in claim 2, wherein said rotary auxiliary distributing member is a rectifier roll of known construction.

4. A distributing system for suspensions of fibrous materials to be supplied through feed pipe means to the system and delivered from there to a dehydrating machine, comprising, in combination, a headbox, one primary distributing chamber to which said feed pipe means are connected, said primary distributing chamber having one outlet slit-shaped opening in the uppermost part thereof; a secondary distributing chamber having one diffusor section merged therewith, said diffusor section having an entrance opening and two opposite walls extending over the whole length of the primary and secondary distributing chambers and diverging from said entrance opening towards said secondary distributing chamber by an angle of at least 8° up to approximately 30°, said diffusor section being connected by way of said entrance opening to said outlet opening in said primary distributing chamber, and further comprising at least one perforated roll of known construction as a rotary auxiliary distributing member in said diffusor section, said secondary distributing chamber having an outlet in the highest part for connection of said headbox thereto.

5. A distributing system for suspensions of fibrous materials to be supplied through feed pipe means to the system and delivered from there to a dehydrating machine, comprising, in combination, a headbox, one primary distributing chamber to which said feed pipe means are connected, said primary distributing chamber having one outlet slit-shaped opening in the uppermost part thereof; a secondary distributing chamber having one diffusor section merged therewith, said diffusor section having an entrance opening and two opposite walls extending over the whole length of the primary and secondary distributing chambers and diverging from said entrance opening towards said secondary distributing chamber by an angle of at least 8° up to approximately 30°, said diffusor section being connected by way of said entrance opening and a short conduit of substantially constant cross sectional area to said outlet opening in said primary distributing chamber, and further comprising at least one rotary auxiliary distributing member in said diffusor section, said secondary distributing chamber having an outlet in the highest part for connection of said headbox thereto.

6. A distributing system for suspensions of fibrous materials to be supplied through feed pipe means to the system and delivered from there to a dehydrating machine, comprising, in combination, a headbox, one primary distributing chamber to which said feed pipe means are connected, said primary distributing chamber having one outlet slit-shaped opening in the uppermost part thereof; a secondary distributing chamber having one diffusor section merged therewith, said diffusor section having an entrance opening and two opposite walls extending over the whole length of the primary and secondary distributing chambers and diverging from said entrance opening towards said secondary distributing chamber by an angle of at least 8° up to approximately 30°, further comprising a plurality of rotary auxiliary distributing members disposed in the interior of said diffusor section in series and with increasing diameters in the direction of suspension flow through said diffusor section, said diffusor section being connected by way of said entrance opening to said outlet opening in said primary dis-

tributing chamber, said secondary distributing chamber having an outlet in the highest part for connection of said headbox thereto.

7. A distributing system for suspensions of fibrous materials to be supplied through feed pipe means to the system and delivered from there to a dehydrating machine, comprising, in combination, a headbox, one primary distributing chamber to which said feed pipe means are connected, said primary distributing chamber having one outlet slit-shaped opening in the uppermost part thereof; a secondary distributing chamber having one diffusor section merged therewith, said diffusor section having an entrance opening and two opposite walls extending over the whole length of the primary and secondary distributing chambers and diverging from said entrance opening towards said secondary distributing chamber by an angle of at least 8° up to approximately 30°, further comprising a plurality of rotary auxiliary distributing members disposed in said diffusor section in alignment transversely to the direction of suspension flow through said diffusor section, said diffusor section being connected by way of said entrance opening to said outlet opening in said primary distributing chamber, said secondary distributing chamber having an outlet in the highest part for connection of said headbox thereto.

8. A distributing system for suspensions of fibrous materials to be supplied through feed pipe means to the system and delivered from there to a dehydrating machine, comprising, in combination, a headbox, one primary distributing chamber to which said feed pipe means are connected, said primary distributing chamber having one outlet slit-shaped opening in the uppermost part thereof; a secondary distributing chamber having one diffusor section merged therewith, said diffusor section having an entrance opening and two opposite walls extending over the whole length of the primary and secondary distributing chambers and diverging from said entrance opening towards said secondary distributing chamber by an angle of at least 8° up to approximately 30°, further comprising a plurality of rotary auxiliary distributing members disposed in the interior of said diffusor section in series and with their axes located on an arc the center of which is disposed toward said diffusor section entrance, said diffusor section being connected by way of said entrance opening to said outlet opening in said primary distributing chamber, said secondary distributing chamber having an outlet in the highest part for connection of said headbox thereto.

9. A distributing system for suspensions of fibrous materials to be supplied through feed pipe means to the system and delivered from there to a dehydrating machine, comprising, in combination, a headbox, one primary distributing chamber to which said feed pipe means are connected, said primary distributing chamber having one outlet slit-shaped opening in the uppermost part thereof; a secondary distributing chamber having one diffusor section merged therewith, said diffusor section having an entrance opening and two opposite walls extending over the whole length of the primary and secondary distributing chambers and diverging from said entrance opening towards said secondary distributing chamber by an angle of at least 8° up to approximately 30°, further comprising a plurality of rotary auxiliary distributing members disposed in said diffusor section in several groups, the members of each group being in alignment with each other transversely to the direction of suspension flow through said diffusor section, said groups being disposed one behind the other in the direction of suspension flow therethrough, said diffusor section being connected by way of said entrance opening to said outlet opening in said primary distributing chamber, said secondary distributing chamber having an outlet in the highest part for connection of said headbox thereto.

10. A distributing system for suspensions of fibrous materials to be supplied through feed pipe means to the

system and delivered from there to a dehydrating machine, comprising, in combination, a headbox, one primary distributing chamber to which said feed pipe means are connected, said primary distributing chamber having one outlet slit-shaped opening in the uppermost part thereof; a secondary distributing chamber having one diffusor section merged therewith, said diffusor section having an entrance opening and two opposite walls extending over the whole length of the primary and secondary distributing chambers and diverging from said entrance opening towards said secondary distributing chamber by an angle of at least 8° up to approximately 30° , further comprising a plurality of rotary auxiliary distributing members disposed in said diffusor section in several groups, the members of each group being in alignment with each other transversely to the direction of suspension flow through said diffusor section, said groups being disposed one behind the other in the direction of suspension flow therethrough, the members of one of said groups being staggered with regard to the members of the group preceding said one group in the direction of suspension flow, said diffusor section being connected by way of said entrance opening to said outlet opening in said primary distributing chamber, said secondary distributing chamber having an outlet in the highest part for connection of 25 said headbox thereto.

11. A distributing system for suspensions of fibrous materials to be supplied through feed pipe means to the system and delivered from there to a dehydrating machine, comprising, in combination, a headbox, one primary distributing chamber to which said feed pipe means are connected, said primary distributing chamber having one outlet slit-shaped opening in the uppermost part thereof; a secondary distributing chamber having one diffusor section merged therewith, said diffusor section having an entrance opening and two opposite walls extending over the whole length of the primary and secondary distributing chambers and diverging from said entrance opening towards said secondary distributing chamber by an angle of at least about 3° and up to about 8° , and wherein the 40 interior of said diffusor section is free for unimpeded suspension flow, said diffusor section being connected by way of said entrance opening to said outlet opening in said primary distributing chamber, said secondary distributing chamber having an outlet in the highest part 45 for connection of said headbox thereto.

12. A distributing system for suspensions of fibrous ma-

terials to be supplied through feed pipe means to the system and delivered from there to a dehydrating machine, comprising, in combination, a headbox, one primary distributing chamber to which said feed pipe means are connected, said primary distributing chamber having one outlet slit-shaped opening in the uppermost part thereof; a secondary distributing chamber having one diffusor section merged therewith, said diffusor section having an entrance opening and two opposite walls extending over the whole length of the primary and secondary distributing chambers and diverging from said entrance opening towards said secondary distributing chamber by an angle of at least about 3° and up to about 8° , wherein the ratio $L:D$ is at least 5 and up to 10 and higher, L being the length of the diffusor section and D the diameter of said secondary distributing chamber at right angle to the diffusor section in a plane parallel to the direction of current flow, and wherein the interior of said diffusor section is free for unimpeded suspension flow, said diffusor section being connected by way of said entrance opening to said outlet opening in said primary distributing chamber, said secondary distributing chamber having an outlet in the highest part for connection of said headbox thereto.
